(57) CLAIM

The ornamental design for a digital recorder, as shown and described.

DESCRIPTION

FIG. 1 is a front perspective view of a digital recorder showing my new design;

FIG. 2 is a front view of the digital recorder of FIG. 1; FIG. 3 is a left side view of the digital recorder of FIG. 1; FIG. 4 is a bottom view of the digital recorder of FIG. 1; FIG. 5 is a right side view of the digital recorder of FIG. 1; FIG. 6 is a top view of the digital recorder of FIG. 1; FIG. 7 is a rear view of the digital recorder of FIG. 1; and, FIG. 8 is a rear perspective view of the digital recorder of FIG. 1.

The broken lines are included for the purpose of illustrating unclaimed portions of the digital recorder and form no part of the claimed design.
